No. 13319

Design

UNITED STATES PATENT OFFICE.

RIVERIUS MARSH, OF NEW BRUNSWICK, NEW JERSEY.

DESIGN FOR A LAMP-BRACKET.

SPECIFICATION forming part of Design No. 13,319, dated September 26, 1882.

Application filed August 28, 1882. Term of patent 3½ years.

To all whom it may concern:

Be it known that I, RIVERIUS MARSH, a citizen of the United States, residing at New Brunswick, in the county of Middlesex and State of New Jersey, have invented and produced a new and original Design for Lamp-Brackets, of which the following is a specification, reference being had to the accompanying photographs, forming a part thereof.

1c The photograph represents a side view of my newly-designed lamp-bracket.

The leading features of my design are two branches of a broken and leafless tree. Berries or fruit are shown on the outer ends of the branches, and a male figure is represented as standing between the branches. On the arm of the bracket a swan with raised wings is represented as resting on water with foliage before and above the swan, the foliage representing flags and grasses, and are united together at different points, forming a scroll-bracket. Extending out beyond the scroll-work and attached to the bottom of the bracket is an or-

namental bar with a key-shaped piece below it, and with a lamp-rest above it. At the large 25 end of the bracket, and extending out from the broken trunk of the tree, is a hook or projection for fastening or hanging the bracket to the wall-piece. The wall-piece can be made of any ornamental design, and with an eye in the 30 front to receive the hook or projection on the back of the bracket.

I claim—

The design for a lamp-bracket herein shown and described, the same consisting of the broken tree and its leafless branches and fruit, the male figure between the branches, the swan resting on the water, the flags and foliage beyond, above, and before the swan, and the ornamental bar with its key-shaped piece and 40 lamp-rest.

RIVERIUS MARSH.
